DOLPHIN-SHAPED SEAT FOR PLAYGROUND APPARATUS

Robert S. Wormser, Hillsdale, Mich., assignor to Game Time, Inc., Litchfield, Mich., a corporation of Michigan

Filed Dec. 30, 1968, Ser. No. 15,138

Term of patent 14 years

Int. Cl. D21—04

U.S. Cl. D34—15

FIG. 1

FIG. 3

FIG. 1 is a side, elevational view of the right side of a dolphin-shaped seat for playground apparatus in accord with my new design, the left side being identical thereto in appearance,

FIG. 2 is a top plan view,

FIG. 3 is a front, elevational view in accord with my new design, and

FIG. 4 is a rear, elevational view.

I claim:

The ornamental design for a dolphin-shaped seat for playground apparatus, substantially as shown and described.
